HOUSING FOR AN ARTIFICIAL EAR

Clifford A. Nygard, Phoenix, Ariz., assignor to Royal Industries, Inc., Pasadena, Calif.

Filed Jan. 17, 1972, Ser. No. 218,649

Term of patent 14 years

Int. Cl. D14—01
U.S. Cl. D26—14 H

FIG. 1

FIG. 2

FIG. 3

FIG. 1 is a front elevational view of the housing for an artificial ear showing my new design;

FIG. 2 is a top plan view of the housing for an artificial ear taken along the line 2—2 as illustrated in FIG. 1; and

FIG. 3 is a rear end plan view of the housing for an artificial ear taken along the line 3—3 as illustrated in FIG. 1.

I claim:

The ornamental design for the housing for an artificial ear, as shown.
